(57) **CLAIM**

The ornamental design for an ergo calculator, as shown and described.

DESCRIPTION

FIG. 1 is a perspective view of an ergo calculator showing our new design;

FIG. 2 shows a front elevation view thereof;

FIG. 3 shows a rear elevation view thereof;

FIG. 4 shows a left side elevation view thereof;

FIG. 5 shows bottom plan view thereof shown in larger scale; and,

FIG. 6 shows a top plan view thereof shown in larger scale. The broken lines depict environmental structure only and form no part of the claimed design.
